M. H. Elmore

M. H. Elmore of Buffalo, N.Y.

Letters Patent No. 2088 Dated June 19, 1865.

DES. 2088

Design for a Music Stand.

The schedule referred to in these Letters Patent and making part of the same.

To all whom it may concern:

Be it known that G. H. Elmore, of the
City of Buffalo, County of Erie, and State of New York, has invented
and designed an ornamental music stand for holding
loose sheets of music and music books, of which the following
is a full and exact description, reference being had
to the accompanying drawings making a part of this specification.

The design consists essentially in supporting a
shallow basket constructed of wire or other suitable material
and one or more shelves beneath the same in a light
ornamental cast iron frame or stand to form a con-
venient receptacle for loose sheets and books of music.

(With the drawings (which is a side elevation of
the stand.) A represents the shallow basket in which
the loose sheets of music may be laid. B, B, represent the
shelves for the reception of the bound volumes or books of
music. C, C, represent the cast iron frame or support
or pedestal. This frame consists of a central column or shaft
C, with radiating feet C¹, formed by an ornamental com-
bination of scrolls and carvings as represented, and the
shelf and basket supports C², also formed of scrolls and
carvings similar in configuration and design to the feet C¹.

What I claim as my invention and desire to secure
by Letters Patent is the ornamental design for a music stand
or holder herein described.

Witness,

H. H. Forbush,

W. W. 10/11/1865
G. J. Prince
